UNITED STATES PATENT OFFICE.

THOMAS SHIPLEY, OF YORK, PENNSYLVANIA.

ICE-CUTTING MACHINE.

988,938.

Specification of Letters Patent. Patented Mar. 28, 1911.

Application filed January 4, 1911. Serial No. 600,772.

To all whom it may concern:

Be it known that I, THOMAS SHIPLEY, a citizen of the United States, and a resident of York, in the county of York and State of Pennsylvania, have invented certain new and useful Improvements in Ice-Cutting Machines, of which the following is a specification.

My invention relates to machines designed 10 to cut large plates or slabs of ice into smaller sizes of blocks convenient for handling and shipment; for which purpose it has been usual to make the cutter capable of movement in two directions at right angles to 15 each other over the surface of the slab, in order to subdivide the latter into smaller blocks of rectangular shape.

The object of my invention is to produce a simple, economical and efficient machine of 20 the kind in question, to which end the invention consists in the combination and arrangement of parts hereinafter described and claimed, the main characteristic of the same being, that the frame in which the saw 25 is mounted, and which in turn is mounted in the motor carriage, is rotatable, independently of the motor, about a center coincident with the axis of revolution of a vertical spindle connected on the one hand to the 30 motor and on the other hand to the saw mandrel, whereby the saw frame can be turned to bring the saw into any desired position with reference to the ice to be cut without any corresponding movement of the 35 motor, and without disturbing the motion transmitting mechanism between the motor and the saw.

In the accompanying drawings, to which I shall now refer for a better understanding 40 of my invention: Figure 1 is a plan, and Fig. 2 is a side elevation, of the machine. The remaining figures are on larger scale and are designed to illustrate structural details which can not be conveniently represented 45 on smaller scale. Fig. 3 is a plan of the motor carriage and attached parts and a portion of the track system, the motor being removed and a portion of the motor base (forming the top of the carriage) being 50 broken away. In this figure the hand wheels for operating the saw frame, and the motor

carriage, etc., are removed. Fig. 4 is a transverse vertical section on line 4—4, Fig. 3, designed more particularly to show the details of the saw frame or gear box. Fig. 5 is a longitudinal vertical section on line 5—5, Fig. 3, showing also a portion of the bridge and track on which it runs. Fig. 6 is a vertical section on line 6—6, Fig. 3, showing the details of the mechanism for operating the 60 saw frame. Fig. 7 is a section on line 7—7, Fig. 3, showing the details of the stop pin device for holding the saw frame in adjusted position. Fig. 8 is a view of a modification hereinafter referred to. 65

Referring to the general views of the apparatus, Figs. 1 and 2, X is the bridge or truck which bridges the space occupied by the ice slab or cake (dotted lines W, Fig. 2); Y is the track on which it runs; A is the 70 motor carriage, and B an electric motor thereon; Z is the track on the bridge, on which the motor carriage runs. The two tracks Y, Z, are at right angles to one another; and the truck wheels on one side of 75 both the carriage and the bridge have grooved threads, which fit upon the rails on which they run, and prevent the derailment of the motor carriage and the bridge. The motor is used to drive the saw (indicated by 80 the circle S, Fig. 2). The bridge and the motor carriage may be operated by hand or by power as preferred. In the present instance they are designed to be operated by hand. 85

Thus far there is nothing materially new in the apparatus.

In the example shown in Figs. 1-5, the motor—an electric motor—is vertical; and it is mounted on a base B¹, constituting a cap 90 for the main frame A of the motor carriage, which is a casting having the general form of a cylindrical shell (as shown more particularly in Figs. 3, 4, 5) the interior of which is formed with a horizontally projecting 95 annular shelf A¹, which forms a support and bearing for the saw frame C. This saw frame is a hollow casting of the irregular form fully represented in Figs. 3, 4, 5, constituting not only a support for the saw S 100 and saw mandrel S¹, but also a gear box for containing and housing the gearing through

the intermediary of which the saw is driven by the motor. The saw frame is open at top and closed below by a removable bottom cover C⁴; and is provided with a hand hole, 5 closed by a suitable cover C² (Fig. 5). Within it are caged horizontal bearings C³, C⁵, for the saw mandrel and a central caged vertical bearing C⁴ for the vertical spindle D. This spindle is axially arranged 10 with reference to the cylindrical carriage frame A, and is directly driven by the motor; on its lower end is a beveled gear 1, which meshes with a like gear 2 on the saw mandrel. In this way the saw can be driven: 15 practically directly from the motor shaft, of which the spindle D is in effect a prolongation. The motor, instead of being vertical, may occupy a horizontal position, as indicated in Fig. 8, in which event, the motor shaft being at right angles to the spindle D, an additional pair of beveled gears 3, 4, at 20 top will be required to connect the motor with the spindle. I prefer, however, the direct drive arrangement shown in the preceding figures and first above described, because the saw may be driven from the motor by only a single pair of directly connected gears, and because the rotating saw frame C will revolve about the axis of the motor 25 shaft as a center.

The rotary movement of the saw frame C is provided for as follows: The top of the box-like saw frame is cylindrical in form, and is provided with an external horizontal 30 annular flange C⁵, which fits and rests upon the shelf A¹. The saw frame is thus supported by the shelf A¹, and at the same time can be rotated thereon, its flange C⁵ moving over the face of the shelf with which it is in 35 contact. The center upon which the saw frame thus turns is coincident with the axis of revolution of the vertical spindle D; and thus the saw frame may be rotated independently of the motor and motor carriage 40 to bring the saw into any desired position relatively to the ice to be cut, without in any way disturbing the driving connections between the motor and the saw. In order to thus rotate the saw frame, any suitable 45 means may be employed. The means I prefer to use are as follows: The space above the annular flange C⁵, and included between the vertical walls of the saw frame and the motor carriage, forms an annular trough 50 in which is located the toothed segment C⁶, secured to the upper face of flange C⁵. Inasmuch as in this instance the required range of rotary movement of the said frame is 90°, the segment need be of sufficient length only 55 to turn the said frame to that extent. The trough-like annular space in which the toothed segment is located is closed by the rim of the motor base B¹, as indicated more 60 particularly in Fig. 4. The toothed segment is engaged by a pinion 5 located in a

box formed in a boss on the side of the main frame A (see Figs. 1, 3, 6) and mounted on the lower end of shaft E which extends vertically up through a supporting bearing in a boss on the rim of the motor base B¹, and has on its protruding upper end an operating hand wheel E'. By turning the hand wheel the shaft E and its pinion 5 will be rotated with the effect of turning the segment C⁶ and consequently the saw frame C. 75 To lock the saw frame accurately in either of the two positions it is intended, by this rotary movement, to occupy, suitable stop devices can be employed, consisting in the present instance (see Figs. 1 and 7) of a vertical stop pin F movable up and down in a hole in a portion of the motor base B¹ overlying the annular rim of the saw frame in the top of which are two sockets e, e, exactly 90° apart, adapted, one or the other, 80 to be engaged by the stop pin according to the position of the saw frame. The stop pin is operated by a lever F¹ pivoted to a standard F² on the base B¹. Its shorter arm engages the head of the stop pin and its longer arm forms a handle by depressing which the lever will be moved in a direction to lift the stop pin far enough to release it from engagement with the saw frame, against the stress of a spring e¹ 95 which normally presses the lever in a direction to force the stop pin downward.

Instead of making the vertical spindle D continuous, I prefer, as shown in Fig. 4, to divide it into two parts, the opposed ends of which are connected by a universal joint D¹ of some approved pattern, which unites the portion of the spindle that has its bearing in the saw frame, with the portion of the same that is an extension of the motor shaft. In this way I am enabled to compensate for slight changes in the position of the saw frame consequent upon its turning movement, which might otherwise cramp the action of the saw driving instrumentalities. 100

I believe this combination with the motor and motor carriage of a saw frame rotatable independently of the motor to shift the position of the saw, to be new with me.

The saw frame, it will be noted, is a gear box or case as well, and may be filled with oil or grease so that the gears, etc., operating the saw may be run in a lubricant, thus reducing wear to a minimum.

As hereinbefore stated, the travel of the motor carriage and the bridge over their respective tracks, can be effected in any known or suitable way. In the present instance they are hand impelled, through the intermediary of suitable gearing connected to their truck wheels. The mechanism comprises a hand wheel G (Figs. 1, 2, 5) fixed to the top of a vertical operating shaft G¹ supported and rotatable in a bracket bearing G² on the motor carriage frame A. On 115 120 125 130

the lower end of the vertical operating shaft G^1 (referring more particularly to Figs. 3, 5) is a bevel gear 6, which meshes with a corresponding gear 7 on a cross shaft G^2 mounted to revolve in suitable bearings on the motor carriage. On the cross shaft is a loose pinion 8 which meshes with a gear wheel 10 fast on the axle R of the rear truck wheels of the motor carriage. On the cross shaft G^2 beyond the loose pinion 8 is another loose pinion 9 which meshes with a gear wheel 11, supported in a bracket bearing on the motor carriage, said gear wheel 11, through a suitable miter gear 12 which 10 revolves with it meshing with a corresponding miter gear 13 revolving in a sliding bearing 14 and having a splined connection with a shaft H, upon which it can slide lengthwise, while at the same time the two 15 must rotate together. Shaft H, which is supported in end bearings H¹ erected on the bridge, is in operative connection with the end truck wheels of the bridge, through a suitable system of miter gearing 15, 16, 20 17, 18, at each end of the bridge, through the intermediary of which the truck wheels of the bridge will be put in motion whenever the shaft H is rotated. The loose pinions 8, 9, are placed a sufficient distance 25 apart on the cross shaft G^2 , to permit the interposition between them of the sliding member k of a clutch, which is splined on the shaft G^2 , and can, by a suitable shifter s, Fig. 1, be thrown into connection with the 30 opposed face of either one of the loose pinions—these opposed faces being formed each as the other member of the clutch. Rotation of the hand wheel G¹ and operating shaft G^1 , will cause corresponding rotation 35 of the cross shaft G^2 ; and this movement of the cross shaft will be communicated to the truck wheels of either the motor carriage or the bridge, according as the clutch member k is in engagement with either the pinion 8 40 or the pinion 9.

Suitable stop pins are provided for the motor carriage and the bridge respectively, to lock the one in position while the other is in motion.

50 In order to properly support the shaft H, and maintain it in its proper position relatively to the motor carriage, a second sliding bracket bearing attached to and projecting laterally from the motor carriage is provided as shown at m, Fig. 3, this bearing being at the end of the carriage opposite that where the bracket bearing 14 is located.

The motor may be connected to the source of electric supply in any convenient way. 60 In the design illustrated in the drawing the conductors are led through a suitable conduit α erected on one end of the bridge X (Fig. 2) and thence are strung along the near side of the web of one of the longitudinal beams X¹ of the bridge, as indicated in

Fig. 5, where the conductor wires are shown at α , β . On the motor carriage adjoining these wires is fixed a suitable trolley T as shown in Fig. 4 at the left hand side of the carriage. The trolley is in proper electrical connection with the motor, and its wheels engage in the usual way the conductor wires α , β (shown in section in Fig. 4) as will be understood without further explanation.

Having described my improvements, and the best way now known to me of carrying the same into practical effect, I state in conclusion that I do not limit myself to the structural details hereinbefore described and illustrated, since manifestly the same can be widely varied without departure from the spirit of my invention; but

What I claim herein as new and desire to secure by Letters Patent is as follows:

1. The combination with the traveling bridge, the motor, and the motor carriage mounted and adapted to travel on the bridge and provided with an annular horizontal saw-frame-supporting shelf or bearing, of the saw frame resting upon, and supported by, said horizontal annular shelf or bearing and free to turn thereon independently of the motor and motor carriage, a saw rotatably mounted in the saw frame, and motion transmitting mechanism connected on the one hand with the motor and on the other hand with the saw, substantially as and for the purposes hereinbefore set forth. 85

2. The combination of the traveling bridge, the motor, the motor carriage mounted and adapted to travel on the bridge, the saw frame carried by the motor carriage and rotatably mounted thereon to turn upon a vertical axis independently of the motor and motor carriage, a rotary saw mounted in the saw frame, and a vertical revoluble spindle, at the upper end connected to, and driven from, the motor, and at the lower end supported in bearings in the saw frame and geared to and adapted to drive the saw, substantially as and for the purposes hereinbefore set forth. 100

3. The combination with the motor carriage and the saw driving motor thereon, of a saw frame mounted to rotate in said carriage upon a vertical axis independently of the motor, a saw rotatably mounted in the saw frame, and a vertical revoluble spindle divided into two parts whose opposed ends are united by a universal joint, the upper part connected to and driven by the motor, the lower part supported in bearings in the saw frame and geared to and adapted to drive the saw, substantially as and for the purposes hereinbefore set forth. 115

4. The combination with the motor carriage and the motor thereon, of a saw frame mounted to rotate in said carriage upon a vertical axis independently of the motor, and formed as a depending box or case, a 120

130

saw mounted in the lower part of said box, motion transmitting devices between the motor and the saw comprising as one of its members a vertical spindle having its axis of revolution coincident with the center on which the saw frame turns, and gearing located within the box-like saw frame and operatively connecting the lower end of the

spindle with the saw, substantially as and for the purposes hereinbefore set forth. 10

In testimony whereof I affix my signature in presence of two witnesses.

THOMAS SHIPLEY.
